UNITED STATES PATENT OFFICE.

DANIEL RATHER, JR., AND SAMUEL RATHER, OF HOLLY SPRINGS, MISS.

SORGHUM-EVAPORATOR.

SPECIFICATION forming part of Letters Patent No. 312,510, dated February 17, 1885.

Application filed November 5, 1884. (No model.)

To all whom it may concern:

Be it known that we, DANIEL RATHER, Jr., and SAMUEL RATHER, citizens of the United States of America, residing at Holly Springs, in the county of Marshall and State of Mississippi, have invented certain new and useful Improvements in Sorghum-Evaporators, of which the following is a specification, reference being had therein to the accompanying drawings.

Our invention pertains to an improvement in sorghum evaporators or pans for evaporating saccharine liquids; and it consists in the peculiar construction, combination, and arrangement of the parts, substantially as hereinafter more fully shown and described.

In the accompanying drawings, Figure 1 is a plan view of our invention. Fig. 2 is a longitudinal sectional view on the line *x x*. Fig. 3 is a detail perspective view, and Fig. 4 is a detail view.

In constructing our sorghum-evaporator we interpose between two longitudinal spaced-apart troughs, A, a series of transverse troughs or pans, B, and rigidly secure together these troughs and pans by means of the transverse nutted bolts C, the pans B being elevated above the plane of the bottom of the longitudinal trough, as more clearly shown in Fig. 2. The wooden troughs A are divided in several distinct apartments by the transverse partitions *a* and *b*, the upper part of the metallic partition *a* being provided with the apertures *a'*, to admit passage of the fluid while excluding the scum which rises to the surface, and the upper part of wooden partitions *b* extending upward to the same height as the apertures *a'*. The wooden partitions *b* are secured in position by ordinary means, and the metallic partitions *a* are removably disposed in the vertical slots *b'*. The wooden troughs A are shielded as against excessive heat by longitudinal metallic shield-strips A', which are bent at right angles and projected up against the metallic troughs B, as shown at *a''*, and between these metallic shield-strips and the wooden troughs A are interposed asbestos packing as additional means of preventing the longitudinal wooden troughs A from becoming overheated or charred. The wooden troughs A, (see Fig. 1,) which consist of the two corresponding vertical walls C,

the bottom C'', securely and tightly attached thereto by ordinary means, and the intermediate end pieces, C², are slotted at C³ for admission of the lateral open ends of the walls of the metallic pans or transverse troughs B. The lateral ends of the bottom of each trough B are respectively provided with the right-angled clutch projections *d*, which are driven down vertically into the bottom piece of the wooden troughs A preliminary to securing to the wooden troughs the outer pieces, C'. The corresponding apertures *d'* serve to admit the flow of the fluid at the bottom of the pan B into the wooden troughs A. The walls *e* of pans B on the left-hand side are higher than those on its right, excepting the outer wall, *f*, of the right-hand pan, which is of corresponding altitude with the walls of pan B on the right hand. The pipe D, designed for egress of the fluid, is provided with an ordinary stop-cock, and the fluid is supplied to the evaporator-pan at the opposite end thereof. Thus constructed, the scum, which floats upon the top of the pans or apartments, may be readily collected and removed, and the heavier part of the fluid be drawn off at intervals through the stop-cock. As the side troughs are wooden, their wooden bottoms being protected as against combustion by a metallic covering secured thereto and asbestos inserted between the metal and the wood, it follows that the juice in the central series of pans obtains a greater temperature than that in the troughs, and that the cooling influence of the latter constantly tends to change its character and consistency, and thus burning of the sorghum-juice in the central pans is prevented by the cooling influence of the juice in the side troughs.

We are aware that it is not broadly new to construct a sorghum-evaporator comprising a series of pans flanked by partitioned side troughs, the parts being held together by means of wooden side pieces secured by nutted iron rods; but the use of wooden troughs, the method of protecting them against combustion, and the peculiar construction of the pans shown comprise our improvements.

Having thus fully described our invention, what we claim, and desire to secure by Letters Patent, is—

1. The combination of the pans B, having

right-angular projections *d*, and the wooden troughs A, protected at bottom with asbestos and sheet metal, and the nutted bolts C, substantially as shown, and for the purpose described.

5 2. The combination of the wooden troughs A, protected at bottom with asbestos and sheet metal and partitioned with removable partitions *a*, having apertures *a'* and partitions *b*, pans B, having right-angular projec-

tions *d*, and nutted bolts C, substantially as shown, and for the purpose described.

In testimony whereof we affix our signatures in presence of two witnesses.

DANIEL RATHER, JR.
SAMUEL RATHER.
